CLAIM

The ornamental design for a pot lid rack, as shown and described.

DESCRIPTION

FIG. 1 is a perspective view of a pot lid rack showing my new design;

FIG. 2 is a right view thereof;

FIG. 3 is a front view thereof;

FIG. 4 is a bottom view thereof;

FIG. 5 is a top view thereof; and,

FIG. 6 is another perspective view thereof.

A left view is omitted since the left view is identical to the right view.

A rear view is omitted since the rear view is identical to the front view.

The broken lines depict portions of the Pot lid rack in which the design is embodied that form no part of the claimed design.
